STEAM CIRCULATION HEATING PLANT

Adolf Miersbe, Cologne-on-the-Rhine, Germany

Application April 15, 1931, Serial No. 530,380

1 Claim. (Cl. 237—1)

In steam heating installations in which the steam is in constant circulation, and this steam, at one point in its circuit, is impelled round the circuit by means of an injector or jet pump operated by live steam from an external source, which gives up its heat in the steam circulation heating plant, an important part is played not only by the regulating of the jet pump but also by the complete separation of water and air from the steam flowing through the various pipes and heating units. It is above all important, in steam heating installations of the aforementioned kind, by a skilled construction of the jet pump, in conjunction with other auxiliary means to be fitted into the heating plant, to prevent large accumulation of condensed water, and to prevent accumulations of air being formed from the air that all heating steam ordinarily carries with it. Such accumulations of water and air not only obstruct the free passage of the heating steam within the circulatory system but also impair the delivery of heat to the individual heating elements, ribbed tubes for example.

This object is attained according to the invention by providing, at least at the entrance points of the live steam and of the low pressure steam to be utilized therewith, and preferably also at another suitable point in the circuit of the steam-heating system, means which bring about, besides a thorough separation of water, also the equally important separation of air from the steam, and also by exerting, in place of the single-acting construction of the jet pump hitherto provided, a substantially stronger action, and in particular a double action thereof, upon all the exhaust or low pressure steam entering the system, the possibility of extensive differentiation of the effects of the jet regulation being however retained.

The arrangement of the jet pump is then such that the live steam can enter the nozzles of the jet pump at two different points, so that it is feasible, according to the quantities of heat needed, to allow the live steam to pass through the ejector either by one path only or by two paths, in such a way that when the live steam only passes through one nozzle path of the ejector the acceleration of the circulation and the delivery of heat is not so great as when it passes through the ejector by two nozzle paths simultaneously, as in the latter case it exerts a particularly powerful accelerating action upon the used steam. In this way the action of the ejector can be strengthened or weakened according to the varying external temperatures.

The accompanying drawing shows a diagram-

matic view of a steam circulation heating installation equipped with an ejector according to the invention, the ejector, with the condensed water collector and the return pipes, being shown on a larger scale and in sectional elevation, while the individual heating elements, ribbed tubes for example and heated drums or tanks with their supply pipes, are shown in outside elevation. The plant is only to be regarded as a closed-circulation heating installation in the sense that into the return piping there only enters the steam flowing back from the heating units, and not exhaust steam or low-pressure steam from other steam generators.

The live steam coming from any convenient source of heat, a steam boiler for example, enters the steam circulation pipe system at 1, crosses over a pocket-like structure 3 and under a dome-like structure 2, and then flows through a tubular element 4 or a branch tubular element 8, which lead respectively to the regulating and shut-off members 6 and 8^a of the jet pump 7.

The pocket-like structure 3 is for the purpose of separating any water that may be present in the live steam. The water deposited is removed from time to time through a cock 3^a. In the dome 2, any air carried along by the live steam is separated from the latter. An air-relief cock 2^a or a valve leads the air thus separated into the atmosphere from time to time or continuously.

The greater part of the steam, freed from water and air, collects in the chamber 5 of the jet pump 7, while a smaller quantity passes through a pipe 8 to the stop valve 8^a. From the chamber 5 the steam flows, in quantities determined by the position of the valve 6, into the nozzle-like tapering cavity 10 of the jet pump cone 12, and leaves the mouth thereof at a high speed in the form of a jet, exerting a suction and accelerating action upon a quantity of low pressure or exhaust steam which enters an annular chamber 11 in the jet pump from a pipe 26 opening into the interior of the conical wall 9^a of the chamber 11.

This action is considerably reinforced if at the same time the steam flowing through the branch pipe 8, after the valve 8^a is opened, enters the annular chamber 9, which is formed by a nozzle-like part 12^a of the jet pump 7, which surrounds the part 9^a at a suitable distance. The maximum attainable acceleration is thereby exerted upon the exhaust steam in the intermediate nozzle or annular chamber 11, which is already influenced by the injector action of the nozzle 10, any desired variation in the relative quantities and velocities of the steam entering through the pipes

1, 8 and 26 being attainable by adjusting the valves 6 and 8^a.

From the jet pump the steam, freed from water and air, flows at a high speed, owing to pressure imparted to it by the boiler, through a distributor pipe 13 to the individual heating units, for instance to ribbed tubes 14 and 14^a, and to drying cylinders 15 and 15^a and the like. Valves 17^a, 17^b, 17^c and 17^d provided in the inlet pipes 16^a, 16^b and 16^c enable the quantities entering the respective pipes to be regulated.

The steam leaving the heating units 14, 14^a, 15 and 15^a passes through pipe units 18, 18^a, 18^b and 18^c into a return pipe 19.

15 This return pipe according to the invention may consist of separate pipes opening into a common water separator 22, and corresponding in number to the individual heating units, in which case, in order to obviate losses of heat, the arrangement might be such that all these pipes were enclosed, concentrically or eccentrically in relation to one another, as a nest of tubes in a common jacket pipe.

20 A preferred arrangement, however, is to employ as a return pipe a single pipe 19 and to divide it into a number of compartments by means of partitions 19^a, the return pipes 18, 18^a, 18^b and 18^c being so connected to the compartments of the pipe 19 as to ensure conditions that are as 25 equal as possible as regards temperature and steam pressure.

25 If for example the steam pressure in the heating units 14^a and 15 amounts to one atmosphere and that in the heating units 14 and 15^a to two atmospheres, the compartment 19^b of the pipe 19 will preferably be connected with the units 14 and 15^a, and the compartment 19^c, with the units 14^a and 15, but provision will nevertheless be made, by arranging a common air-collecting dome 20, 30 with air-relief valve 20^a, for a certain equalization of the pressures in the pipe 19, at the same time also effecting a further removal of air from the returning steam flowing through the latter.

35 Now the return steam flows out of the pipe 19 into a common connecting piece 21 between the pipe line 19 and the separator and collecting chamber 22.

40 It is advisable to construct the passages 21^a and 21^b of the connecting member 21 as nozzles, in order to increase the velocity of the

return steam at its entrance into the collector 22, and to arrange in front of the nozzle outlets 21^c and 21^d inclined baffle plates 23^a and 23^b on a holder 23 in the chamber 22 in order likewise to promote a further separation of water from the entering steam. The water accumulating in the chamber 22 falls to the bottom and flows away into a steam trap 24, which is connected with the chamber 22, and from which it is withdrawn or discharged at 25.

45 To the top of the collector 22 is connected a pipe 27, with a further air relief-dome 27^a and a water pocket 27^b, the accumulations of water passing through an aperture 27^d into the collector 22, while an air-relief valve 27^c periodically or continuously allows the accumulating air to escape to the atmosphere. The return steam or exhaust steam thus freed from water and air now passes through the pipe 26, and the non-return valve 28 interposed therein, and through an inlet 29 into the intermediate nozzle 11 of the jet pump 7, so that the circuit is closed, and the series of operations already described continues indefinitely.

50 What I claim is:—

A steam circulation heating installation, comprising a pipe line for supplying live steam, a jet pump interposed in the pipe line, means for regulating the flow of live steam through the jet pump, heating units connected to the pipe line for utilizing the steam supplied by the jet pump for heating purposes, a return pipe line for the used steam from the heating units, a chamber interposed in the return pipe line, a baffle plate in the chamber, a dome surmounting the chamber and communicating with the interior thereof, and a second baffle plate in the dome, the return pipe having its cross section tapered like a nozzle to increase the velocity of the used steam at the point where it enters the chamber and being directed towards the baffle plate in the chamber for the interruption of condensate, and the baffle plate in the dome being adapted to constrain steam leaving the chamber to pass up into and then down out of the dome for the removal of air from the steam, the return pipe line being so connected to the jet pump that the used steam, after leaving the steam dome, is recirculated through the installation.
